UNITED STATES PATENT OFFICE.

MOSES M. LAHUE, OF LOWELL, MASSACHUSETTS.

BRUSH.

1,135,590.

Specification of Letters Patent. Patented Apr. 13, 1915.

Application filed May 16, 1910. Serial No. 561,533.

To all whom it may concern:

Be it known that I, Moses M. LAHUE, a citizen of the United States, residing at Lowell, in the county of Middlesex, State of Massachusetts, have invented a certain new and useful Improvement in Brushes, of which the following is a specification, reference being had therein to the accompanying drawings.

10 The invention has relation to brushes, and is more particularly an improvement in brushes of the class in which the bristles are secured by being clasped between wires that are twisted together, prolongations of said 15 wires having connected therewith and secured thereto the handle of the brush. One type of brush of this class is shown and described in Letters Patent of the United 20 States, No. 726,544, granted to me April 28, 1903.

One general object of my present invention is to provide in improved manner for connecting and combining a handle with the bristle-carrying wire stem of a brush of 25 the class mentioned.

The nature of the invention will best be understood from the following description of certain embodiments thereof chosen for illustrative purposes and shown in the accompanying drawings, in which,—

Figure 1 is an elevation, partly in section, of a brush on the order of that of my Letters Patent aforesaid and having the present invention applied thereto. Fig. 2 shows in 35 central longitudinal section a brush of a different construction having the invention embodied therein.

Referring first to Fig. 1, the bristles are marked 1, the wire stem is shown at 2, a trough-shaped back constituting what I term the head of the brush is designated 3, and a handle is shown at 4. As in the patent referred to, the bristles 1 are secured in place between the intertwined wires 40 forming the stem 2, the said bristles projecting transversely from the said stem and being held in place during the twisting of the wires by a suitable adhesive, such as pitch, shellac, or the like, the said adhesive 45 serving as an additional securing means for the bristles after the completion of the brush. The trough-shaped back 3, as in the patent referred to, incloses the bristle-holding portion of the wire stem 2, and also 50 incloses portions of the bristles adjacent the wire stem, and clasps said bristles between 55

its edges so as to hold them compressed together. The lower end 5 of the stem is bent back upon itself, inserted into a hole 6 in the metal back, and clenched securely. 60 For convenience of designation, the metal back is also as above termed a head, for the purposes of this case.

In accordance with the present invention the handle 4 is formed with a hole or bore 7 extending longitudinally therethrough, and at its lower end in Fig. 1 is formed with a counter-bore 8. The prolongation of the wire stem 2 extends through the said counter-bore and bore, and the upper end of the 70 trough-shaped metal back or head 3, is seated in the counter-bore 8, which it snugly fits. A ferrule 9 is applied to the lower end of the handle, around the portion receiving the upper end of the trough-shaped metal 75 back. The free extremity of the wire stem projects at the upper end of the handle and is bent back upon itself and clenched at 10, forming an open eye or loop constituting a suspension device by means of which the 80 brush may be hung upon a hook or nail.

In my patent aforesaid the trough-shaped metal back extends a short distance along the bare portion of the twisted stem above the bristles, but only a fraction of the distance between the bristles and the handle. In the embodiment of my present invention shown in Fig. 1 the said metal back or head extends the whole distance between the bristles and the handle, and is engaged with 90 the handle itself, as already explained, producing thereby a stiffer, stronger, more durable, and more satisfactory brush.

The eye or loop 10 formed in the wire stem constitutes a lock by which the handle 95 and stem are secured together and the parts of the brush are held firmly in proper working relations.

In the construction shown in Fig. 2 the handle portion 11 is provided with a longitudinal bore 12 and at its lower end in Fig. 2 with a counter-bore 13, while the twisted wire stem 14 is provided adjacent one end with bristles 15 and is secured in place by bending the opposite end, which projects 105 from the handle portion 11 into an open eye or loop 16. These parts all are or may be substantially similar to the corresponding parts of the form of the invention last described. In the embodiment illustrated in 110 Fig. 2, however, the trough-shaped back is omitted and the inner portions of the bristles

received directly in the counter-bore 13, thereby providing an additional hold for the bristles. The mass comprised of the said inner portions of the bristles, immediately adjacent the lower end of the wire stem, constitutes the head-portion of the brush of Fig. 2.

From the foregoing it will be seen that the bristles are securely held in the stem by 10 mechanical means not depending upon adhesives for its operation, while the stem is in a similar manner locked in place in the handle. The construction moreover is 15 simple and inexpensive and, while secure, does not entirely prevent the disassembling of the parts should such be desired.

Brushes embodying the present invention like that of Letters Patent No. 726,544 are 20 designed more especially to be employed in cleaning up dust, lint, etc., upon and around and beneath machinery. In use, they become charged more or less with grease, oil, and the dust, lint, etc., held thereby. As 25 a result, the bristles fill up with a sticky mass rendering it heavy and unwieldy, and materially interfering with the utility of the brush.

With the object in view of enabling the brush to be cleared of the accumulation, and 30 cleansed and made fit for further use, I construct it with reference to fitting it to be soaked and boiled out in a solution of sal-soda, or other suitable detergent or cleansing solution. Thus, I make the handle 4 35 or 11 of material which will be unaffected by the solution employed. For instance, I make the said handle of a suitable metal. I have used aluminum for its lightness. After being properly boiled out, the bristles 40 are in good condition, and the brush is ready for continued use. I am enabled to subject the brush to the boiling-out treatment because of the fact that the bristles are securely held, and the parts locked together, by mechanical means not depending upon adhesives for effective results.

Having thus described my invention, I claim:

1. A brush comprising a handle having

a bore extending longitudinally therethrough, a stem composed of a plurality of lengths of wire having bristles clamped between them adjacent one end of the said lengths, said stem extending through said bore and having its end opposite said bristles 55 projecting therefrom, said projecting end being bent upon itself against one end of the handle for securing said stem in said handle, holding the handle immovably upon the stem and the bent portion constituting 60 a suspension eye or loop, substantially as described.

2. A brush comprising a handle having a bore extending longitudinally therethrough and a counter-bore at one end thereof, a stem 65 formed of a plurality of wires intertwined throughout their length, and bristles clamped between said wires adjacent one end of said stem, with the head of the brush seated in said counter-bore and said stem 70 extending through said bore and having its opposite end projecting therefrom, said projecting end being bent against one end of the handle and thereby locking the handle and stem against endwise movement, substantially as described.

3. A brush comprising a handle having a bore extending longitudinally therethrough and provided further with a counter-bore in one of its ends, a stem having bristles secured thereto adjacent one end thereof, said stem extending through said bore with said bristles adjacent the counter-bored end of said handle, means located at the opposite end of said stem for securing the stem and 80 handle immovably together, and a trough-shaped back inclosing the bristle-holding portion of said stem and portions of said bristles, said back having a portion seated in said counter-bore, substantially as de- 85 scribed.

In testimony whereof I affix my signature in presence of two witnesses.

MOSES M. LAHUE.
